Primary Examiner — Elizabeth J Oswecki(74) *Attorney, Agent, or Firm* — RatnerPrestia(57) **CLAIM**

The ornamental design for a shock-absorbing cap, as shown and described.

DESCRIPTION

FIG. 1 is a perspective view of a shock-absorbing cap showing my new design, with an attachment assembly shown disconnected;

FIG. 2 is a bottom plan view thereof, with the attachment assembly shown connected;

FIG. 3 is a top plan view thereof, with the attachment assembly shown connected;

FIG. 4 is a rear elevation view thereof;

FIG. 5 is a front elevation view thereof;

FIG. 6 is a right side view thereof; and,

FIG. 7 is a left side view thereof.

In the drawings, broken lines indicate environmental structure or boundaries that form no part of the claimed design.
